ALFRED T. KEITH, OF BRIDGEWATER, MASSACHUSETTS.

ADJUSTABLE STRAP-SUPPORT.

1,136,963.

Specification of Letters Patent. Patented Apr. 27, 1915.

Application filed October 10, 1913. Serial No. 794,464.

To all whom it may concern:

Be it known that I, ALFRED T. KEITH, a citizen of the United States, residing at Bridgewater, in the county of Plymouth and 5 State of Massachusetts, have invented a new and useful Adjustable Strap-Support, of which the following is a specification.

My invention relates to means for clamping an object on to the work-bed of a machine-tool, and is designed to be used in connection with a strap bearing at one end upon the support, and at the other end upon said object, the strap being clamped to the work-bed of the machine-tool by means of a bolt 10 engaging said strap and work-bed.

The invention has for its object to provide a strap support adapted to be used within a wide range of elevation from the surface of the work-bed of a machine-tool, and one 20 that may be readily and quickly adjusted to the level of the top of the work on the work-bed with the greatest exactness within the limits of the device and held securely in such adjusted position.

25 Those objects I attain by the mechanism illustrated in the accompanying drawings, in which similar characters of reference indicate corresponding parts throughout the drawings, and in which—

30 Figure 1 is a side elevation of an adjustable strap support embodying my invention, applied to the work-bed of a machine-tool, together with a clamping strap secured by a bolt to the work-bed of the machine-tool, 35 and bearing at one end upon the upper surface of the adjustable support, and at the other end upon a piece of work clamped to the work-bed of the machine-tool. Fig. 2 is a horizontal transverse section taken on the 40 line 2—2 of Fig. 1.

As illustrated in the drawings, 1 represents a base section having a smooth or unserrated inclined recessed face 2, and oppositely disposed inclined outer ribs 3. The 45 base section 1 is also provided with a longitudinal slot 4 extending transversely from the inclined recessed face 2 of the base section, through the body and opposite wall of said section; and in length from the dotted line 5 to the dotted line 6 of Fig. 1. An adjustable section 7 is mounted upon the base section 1 and is also provided with an inclined smooth or unserrated face 8 that has a sliding engagement with the inclined face 55 2 of the base section 1, the lateral walls of

said face 8 bearing against the inner side walls of the ribs 3 of the base section 1. The adjustable section 7 is provided with a clamping device, preferably a bolt 9, having an angular shoulder 10 engaging a corresponding opening in the lower portion of the adjustable section, and a bolt head 11, the opposite end of said bolt being threaded to engage a thumb nut 12 which bears against the vertical back of the base section. 60 The adjustable section 7 is also provided with an offset shoulder 13 forming a step adapted to support the end of a strap where a comparatively low adjustment is desired. The upper surface 14 of the adjustable section 7 is designed to support and hold firmly in position one end of a strap 15. The opposite end of said strap is designed to bear on an object 16 supported upon the work-bed 17 of a machine-tool. A slot or recess 75 18 may be formed in the work-bed of the machine-tool to engage the head 19 of a bolt 20, while the upper threaded end of the bolt extends through an opening formed in the strap 15 and engages a nut 21, by means of which the strap may be clamped tightly on to the support and the work. The adjustable section 7 is preferably cut away on its upper portion to form an opening 22, so as to reduce the weight and bulk of the support 80 as much as possible, without taking away from its efficiency, at the same time providing a handle or gripping surface 23 by means of which the support may be conveniently carried. 85

It is important that a strap employed for clamping a piece of work to the work-bed of a machine-tool shall bear evenly on the work so as to obtain the strongest grip possible; and to that end it is important that 95 the means designed to support the opposite end of the strap be adjusted at exactly the level or height of the work to be clamped to the work-bed. If the adjustment of the strap support be determined by or dependent upon teeth or serrations, an exact, even adjustment of the level of the bearing surface of the strap support and the upper surface of the work cannot be readily obtained, and therefore the respective ends of the 100 strap do not bear evenly on the work and the support, and the work is not clamped as firmly and securely to the work-bed as it should be. 105

In the device herein shown and described, 110

the adjustable section has a sliding engagement with the base section, and it consequently can be adjusted at any desired point relatively to the base section, no matter how fine an adjustment may be desired in order to bring the upper or supporting surface 14 of the adjustable section on a level with the upper surface of the work 16. The special means herein provided for clamping the adjustable section to the base section enable the upper bearing surface of the adjustable section to be quickly, as well as accurately, adjusted to the level of the work to be clamped on the work-bed, for the reason that the bolt when in use has a variable effective or working length depending on the position of the adjustable member on its base, and when the thumb nut 12 on the bolt 9 is screwed up against the vertical back of the base section, the upper or adjustable section 7 is locked against any downward movement of the adjustable section. In applying the strap support in actual use, the surface 14 of the adjustable section may be placed slightly above the level of the upper surface of the work 16 and the strap 15 placed on the work and the support. By gradually retracting the thumb nut 12 on the bolt 9, the adjustable section 7 is permitted, with the greatest nicety, to descend on the base section, until the supporting surface 14 of the adjustable section is in exact alinement, and level with the upper surface of the work 16. The nut 21 on the bolt 20 is then brought down tight 35 on the strap 15 and the ends of the strap 15 bear firm and true on the support and the work, thereby firmly clamping the work to the work-bed.

There are occasions at times for clamping 40 to the work-bed of a machine-tool an object, the height of which is below that of the strap support. In such cases the offset step or shoulder 13 is used to support one end of

the strap, instead of using the upper end or auxiliary surface 14 of the support.

What I claim as new and desire to secure by Letters Patent is:—

1. A strap support comprising, a base having a vertical back a smooth vertically inclined face and a slot extending through 50 said base, an adjustable section provided with a smooth vertically inclined face having a sliding engagement with that of the base, a bolt secured to the adjustable section and extending through said slot, and a nut 55 engaging the end of the bolt and the vertical back of the base.

2. A strap support comprising, a base having a vertical back a smooth vertically inclined face and a slot extending through 60 said base, an adjustable section provided with a smooth vertically inclined face having a sliding engagement with that of the base and with an offset shoulder forming a bearing surface intermediate the ends of said 65 adjustable section, a bolt secured to the adjustable section and extending through said slot, and a nut engaging the end of the bolt and the vertical back of the base.

3. A strap support comprising, a base having a vertical back a smooth vertically inclined face and a slot extending through said base, an adjustable section provided with a smooth vertically inclined face having a sliding engagement with that of the 75 base, said section being cut away centrally to form a combined handle and brace, a bolt secured to the adjustable section and extending through said slot, and a nut engaging the end of the bolt and the vertical back 80 of the base.

ALFRED T. KEITH.
